UNITED STATES PATENT OFFICE.

NICHOLAS S. VEDDER, OF TROY, AND TOBIAS S. HEISTER, OF LANSINGBURG,
NEW YORK, ASSIGNORS TO FULLER, WARREN & CO., OF SAME PLACE.

DESIGN FOR A COOKING-STOVE.

Specification forming part of Design No. **8,035**, dated January 26, 1875; application filed January 2, 1875.
[Term of Patent 7 years.]

To all whom it may concern:

Be it known that we, NICHOLAS S. VEDDER, of the city of Troy, in the county of Rensselaer and State of New York, and TOBIAS S. HEISTER, of Lansingburg, in said county of Rensselaer, New York, have jointly invented and produced a new and original Design for Cooking-Stoves, of which the following is a specification, reference being had to the accompanying cut, print, or engraving of a cooking-stove having our said new design.

One part of this invention is the design for the panel A, consisting of its concave forward side between its short front and top ends at right angles to its long straight bottom and rear sides that meet in a right angle, in combination with the intaglio ornamentation, composed of the grain-sheaf b, standing in the rear highest part of the panel, the plow c mainly forward of the sheaf and directed toward the narrow forward part of the panel, and the scythe e and rake f, with or without the representation of either plowed ground, g, or a growing plant or plants, h, all shaped and disposed in the panel, so as to present substantially the same appearance as is represented in the aforesaid engraving.

Another part consists of the design for the oven-door M, composed of the sheaf of grain b, and plow c, with or without either the scythe e, rake f, ground g, or plant or plants h, depressed in the plane surface of the panel A, the scalloped inner border n, the smooth inclined surfaces o surrounding the border n, and the outer ornamented border moldings p, each shaped and all arranged together so as to appear substantially as represented in the aforesaid print.

Another part consists of the design for the rectangular panel or door Q at the end of the fire-chamber, composed of the sheaf of grain j, scythe k, and rake l, depressed in the plane surface of the inner rectangular panel I, the scalloped inner border molding n', the smooth inclined surfaces o' around the border moldings n' and the outer ornamented border molding p', each shaped all arranged together so as to appear substantially as represented in the aforesaid engraving.

Another part consists of the design for the oblong front door W, with arched top, composed of the outer moldings x, the inner scalloped molding y, and the intervening series of ornamentations z, contracted at intervals into sections, each having thereon two projections, a, as shown, and the smooth surface i, having the rectangular apertures m therein, and all shaped and combined so as to appear as represented in the aforesaid cut.

What we claim as our joint invention is—

1. The design for the panel A, consisting of its concave forward side between front and top ends at right angles to straight bottom and rear sides, in combination with the intaglio ornamentation, composed of the sheaf b, plow c, scythe e, and rake f, all shaped and disposed substantially as set forth.

2. The design for the oven-door M, composed of the grain-sheaf b and plow c, with or without the scythe e, rake f, ground g, and plant or plants h, depressed in the panel A, the scalloped inner border n, the inclined plane surfaces o, and the outer ornamental border p, all shaped and arranged together, as shown and described.

3. The design for the raised rectangular panel or door Q, composed of the grain-sheaf j, scythe k, and rake l, depressed in the inner panel I, the scalloped inner border n', the smooth inclined surfaces o', and the outer border p', all shaped and arranged together as described and shown.

4. The design for the front door W, composed of the outer moldings x, the scalloped inner molding y, and the intervening series of ornamentations z, and the smooth surface i, having the rectangular apertures m therein, all shaped and arranged as specified and shown.

In testimony whereof we hereunto subscribe our names this 24th day of December, 1874.

NICHOLAS S. VEDDER.
TOBIAS S. HEISTER.
